UNITED STATES PATENT OFFICE

RICHARD M. CRAIG, OF SAN ANTONIO, TEXAS, ASSIGNOR, BY MESNE ASSIGNMENTS, TO
THOMAS W. MENESEE, OF SAN ANTONIO, TEXAS

DISPLAY APPARATUS

Original application filed December 29, 1925, Serial No. 78,244. Divided and this application filed January 7, 1929. Serial No. 330,933.

This invention relates to display apparatus and more particularly to a sign of the type disclosed in my Patent No. 1,698,219, issued January 8, 1929, of which the present application constitutes a division.

One object of the invention is to provide a sign which may be employed for advertising purposes and will not only attract the attention of a person but be so interesting that it will hold the attention of the observer.

Another object of the invention is to provide a sign having subject matter painted thereon in pigment colors and subjected to the effect of spectral colors emitted by colored lights so that by turning the lights on and off the appearance of the advertising matter upon the sign board may be changed due to the light rays absorbing certain of the pigment colors.

An embodiment of the invention is illustrated in the accompanying drawing wherein there is shown a sign board and companion lighting means.

In the description which is to follow reference will be made to pigment colors, and by this term are meant colored pigments or the colors in which the images are represented on the display surface. Reference will also be made to spectral colors and by this is meant the colors of the spectrum as represented by the colored light rays. Reference will likewise be made to neutral colors, and by neutral colors is meant colors which do not materially change under spectral color illumination or, in other words, those colors which display no decided color characteristics such as relate to primary colors.

The drawing illustrates one application of the principles of the invention and referring thereto it will be seen that the numeral 1 indicates in general the display surface. In this embodiment of the invention, the left hand portion of the display surface is painted to provide a dark neutral background 52 and the right hand portion is painted to provide a light neutral background 54. Upon these backgrounds appear in red the words "Spark" and "Plug", indicated by the numerals 51 and 53, and between these words appears a representation of a spark plug 57 which is painted

in some neutral color contrasting with the background 52 and is so disposed upon the sign board that it overlies the dark and light backgrounds. By this arrangement the words "Spark" and "Plug" may be blotted out by spectral rays but the representation of the spark plug will at all times be visible. This is merely one example of advertising matter which may be painted upon the sign board.

The invention contemplates successive illumination of the display surface of the sign by red and blue lights, and while any source of illumination may be employed, it is preferable to arrange, in proximity to the board and in position to illuminate the same, a plurality of red electric light bulbs 5 and blue bulbs 6, the arrangement of the bulbs being such that they will be symmetrically distributed as, for example, in the manner illustrated in the drawing. In this embodiment of the invention, it is contemplated that the two lateral halves of the display surface be successively illuminated by the complementary colors and, therefore, a suitable flashing mechanism is provided which is illustrated diagrammatically in the drawing and indicated in general by the numeral 7. As a suitable example of such a mechanism or device, the same may comprise a disc 8 of insulating material in which are embedded a number of contact strips 9 of arcuate form and other contact strips 10 likewise of arcuate form, the strips being positioned concentric to the axis of rotation of the disc 8 and said strips 9 and 10 being arranged in staggered relation. The numeral 11 indicates the source of current supply and the numeral 12 a conductor wire leading therefrom to, for example, the shaft 13 upon which the disc 8 is mounted, branch wires 14 extending from the shaft to the several contact strips 9 and 10. Brushes 15 and 16 are suitably mounted in juxtaposition to the disc to respectively contact the strips 9 and 10 in the rotation of the disc 8, and another conductor wire 16' is led from the other terminal of the source of current supply and connected to one terminal of each of the sockets for the light bulbs 5 and 6. A con-

ductor wire 17 is connected to the brush 15 and it, and branches leading therefrom, are connected to the other terminals of the sockets for the red light bulbs 5 at the left of the display surface 1, and to the other terminals of the sockets for the blue light bulbs 6 at the right of said display surface, as shown diagrammatically in the drawing. A conductor wire 18 and branches therefrom are connected to the other terminals of the sockets for the blue light bulbs 6 at the left side of the display surface and to the other terminals of the sockets for the red light bulbs 5 at the right hand side of the display surface. The arrangement of the contact strips 9 and 10 is such that, for example, when the receding end of one of the contact strips 9 passes beneath the brush 15, in the rotation of the flasher disc 8, the advancing end of the next adjacent contact strip 10 will ride into electrical contact with the brush 16. Due to the arrangement of the light bulbs and the manner in which they are wired in connection with the flasher device, of whatever character it may be, the red light bulbs 5 at the left hand side of the display surface and the blue light bulbs 6 at the right hand side of the display surface will be simultaneously illuminated for a period of time and, at the moment they are extinguished, the blue light bulbs 6 at the left hand side of the display surface and the red light bulbs 5 at the right hand side of the display surface will be supplied with current. Consequently, at one moment the display surface will be illuminated or displayed in red light rays at the left hand side and blue light rays at the right hand side, and at the next moment, in blue light rays at the left hand side and red light rays at the right hand side.

When the left hand side of the display surface is illuminated by red light rays and the right hand side by blue light rays, the word "Spark" will appear vividly white against a substantially black background and the word "Plug" will appear substantially black against a light neutral background, the spark plug representation 57 being at such time visible due to the fact that it is of a neutral color. On the other hand, when the left hand side of the display surface is illuminated by blue light rays and the right hand side by red light rays, both representations 51 and 53 will be obliterated, although the representation 57 will remain visible.

Having thus described the invention, I claim:

1. Means for displaying the effect of change in appearance of represented matters comprising a display surface having a background represented in contrasting neutral colors and having thereon the matters to be displayed represented in pigment and which pigment representations have no spectral

color difference, and means for displaying said surface successively in the presence of light rays having different color characteristics and one corresponding substantially to the pigment in which the matters are represented. 70

2. Means for displaying the effect of change in appearance of represented matters comprising a display surface having a background represented in contrasting neutral colors and having thereon the matters to be displayed represented in a pigment and which pigment representations have no spectral color difference, and means for successively instantaneously flooding the display surface at non-coincident periods with light rays having different color characteristics and one corresponding substantially to the pigment in which the matters are represented. 75

3. Display apparatus comprising a display surface having thereon, upon contrasting neutral backgrounds, pigment representations of substantially the same color, each upon a respective one of the backgrounds, and means for displaying said surface successively in the presence of light rays having different color characteristics and one corresponding substantially to the color of one of said representations. 80

4. Means for displaying the effect of change in appearance of represented matters comprising a display surface having contrasting neutral background areas, the surface having represented thereon, upon said areas, non-superimposed matters to be displayed represented in pigments of substantially the same color, and means for displaying said surface successively in the presence of light rays having different color characteristics and one corresponding substantially to the color of one of said representations. 95

In testimony whereof I affix my signature.
